WASHING MACHINE AGITATOR

Thomas R. Smith, Newton, Iowa, assignor to The Maytag Company, Newton, Iowa, a corporation of Delaware

Filed Sept. 26, 1966, Ser. No. 4,039

Term of patent 14 years

(Cl. D49—1)

FIGURE 1 is a perspective view of a washing machine agitator showing my new design;

FIGURE 2 is a side elevation view of the washing machine agitator shown in FIGURE 1;

FIGURE 3 is a fragmentary sectional view showing the top of one of the agitator vanes; and

FIGURE 4 is an enlarged fragmentary view showing one of the agitator vanes in side elevation partly in section.

The side not shown has the same appearance as the side shown.

The dominant features of my design reside in the portions shown in full lines.

I claim:

The ornamental design for a washing machine agitator, as shown and described.
